UNITED STATES PATENT OFFICE.

NACHMAN LOWENTHAL, OF CHAMBERSBURG, PENNSYLVANIA.

DESIGN FOR A SHOE.

SPECIFICATION forming part of Design No. 21,752, dated August 2, 1892.

Application filed April 23, 1892. Serial No. 430,418. Term of patent 7 years.

To all whom it may concern:

Be it known that I, NACHMAN LOWENTHAL, a citizen of the United States, residing at Chambersburg, in the county of Franklin and State of Pennsylvania, have invented and produced a new and original Design for Shoe-Linings, of which the following is a specification.

My design has relation to the ornamentation of a shoe. The leading or characteristic feature thereof is a plain band contrasting in shade with the lining and located near the upper edge and passing entirely around from the front opening on the one side to the same opening on the other.

The design is illustrated in the accompanying drawing, in which is shown a side view of a shoe with one side flap turned down.

In said drawing, the letter A designates the shoe; B, the inside lining thereof, and C designates the horizontal band of contrasting shade, which extends around said lining near the top edge and from one side edge of the front opening to the other edge of said opening.

What I claim is—

The design for a shoe, substantially as shown and described.

In testimony whereof I affix my signature in the presence of two witnesses.

NACHMAN LOWENTHAL.

Witnesses:

D. FEDERLEICH,
W. M. BREWER.
